UNITED STATES PATENT OFFICE.

NIMROD P. AGNEW, OF KANSAS CITY, MISSOURI.

COMBINED AUTOMATIC SPINDLE-OILER.

SPECIFICATION forming part of Letters Patent No. 743,371, dated November 3, 1903.

Application filed September 15, 1902. Serial No. 123,394. (No model.)

To all whom it may concern:

Be it known that I, NIMROD P. AGNEW, a citizen of the United States, residing at Kansas City, in the county of Jackson and State 5 of Missouri, have invented new and useful Improvements in Vehicle-Spindle Oilers, of which the following is a specification.

My invention relates to lubricating attachments for vehicle-axles; and it consists of a 10 capped cylinder adapted to hold lubricating fluid, the cylinder being seated in a peripheral hole in the hub, and a wad of wool or similar material within the cylinder in position to wipe the axle, the wad being held by a 15 looped wire secured to the cap of the cylinder.

Referring now to the accompanying drawings, Figure 1 is a transverse section of a vehicle-hub provided with my improved lubricating attachment, the latter being in longitudinal section. Fig. 2 is an elevation of one-half of the hub, omitting spokes, showing the lubricating-cylinder cap projecting from the hub. Fig. 3 is a top plan view of the cap of said cylinder.

1 designates the hub of a wagon or vehicle, 10 the axle or spindle, and 9 the metallic thimble that rotates with the hub.

3 is an externally-threaded cylinder or tube for containing the lubricant. Said cylinder 20 is provided near its upper or outer end with a squared flange or shoulder 3^a.

4 is an internally-threaded cap, having a square portion 4^a, adapted to be turned with a wrench.

35 6 is the upper end of a depending stem, which is permanently secured to the cap 4, either by riveting in the manner shown or in any preferred manner. The lower end of said stem is bent, forming a loop 6^a. Before the

40 loop is closed a wad of wool or similar material is folded around the stem. The loop is then closed. The middle portion of the wad is tightly clasped between the sides of the loop. The wad of wool should be large enough

45 so that it will be compressed by the cylinder 3 when placed therein, and it should extend below the end of the depending stem 6^a, as shown, so that it will slightly engage the spindle when the cap 4 is screwed down upon

50 the flange 3^a. A barb 8 is attached to the stem 6^a. This barb projects upwardly, and its purpose is to more firmly engage the wad

for extraction thereof in case the loop should break.

The wad 7 will automatically admit an 55 even flow of the lubricant to the spindle as long as there is a sufficient quantity of lubricant in the cylinder 3. When the wad runs dry, the cap 4 is partially removed from the cylinder high enough to admit the spout of 60 an oil-can to the interior of the cylinder. The oil is poured in on top of the wad, which is sufficiently porous to let the oil seep through it and keep the spindle lubricated. A suitable quantity of lubricant is placed in the 65 cylinder, and the cap is screwed back in position against the flange 3^a.

Having now fully described my invention, what I claim as new, and desire to secure by Letters Patent of the United States, is—

1. The combination, of an oil-cylinder adapted to be secured in a radial hole in a vehicle-hub and its thimble, with the outer end of said cylinder projecting from the hub, a threaded cap covering the outer end of the 75 cylinder, a wire within the cylinder, one end of said wire being secured to said cap, the other end of the wire being looped, a wad of fibrous material held by said loop, said wad being under compression and sufficiently 80 large to touch the axle, and a barb on the looped portion of said wire, said barb being directed toward said cap, substantially as described.

2. The combination, of an externally-threaded oil-cylinder adapted to be secured in a radial hole in a vehicle-hub and its thimble, with the outer end of said cylinder projecting from the hub, a threaded cap covering the outer end of the cylinder, an internal wire 90 secured to said cap at one end, its other end being doubled upon itself, a wad of woolly material held by said doubled portion of the wire, said wad being under compression and touching the axle, and a barb on said wire with 95 in the wad, said barb being directed toward said cap, substantially as described.

In testimony whereof I affix my signature in the presence of two witnesses.

NIMROD P. AGNEW.
